UNITED STATES PATENT OFFICE.

EDWARD M. COLEMAN, OF CHICAGO, ILLINOIS, ASSIGNOR OF ONE-HALF TO
EMILE CONSTANT, OF ST. PAUL, MINNESOTA.

COMBINED NIPPER AND METER.

SPECIFICATION forming part of Letters Patent No. 683,726, dated October 1, 1901.

Application filed April 23, 1901. Serial No. 57,064. (No model.)

To all whom it may concern:

Be it known that I, EDWARD M. COLEMAN, a citizen of the United States, residing at Chicago, in the county of Cook and State of Illinois, (whose post-office address is 78 West Twenty-fifth street,) have invented certain new and useful Improvements in a Combined Nipper and Meter, of which the following is a specification.

10 My invention relates to improvements in combined twine meters and nippers for spinning-machines; and it consists in the features of combination and construction hereinafter specifically described and claimed.

15 In the accompanying drawings, forming part of this specification, Figure 1 is a vertical cross-section with a portion of the base shown in outline. Fig. 2 is a similar section taken on line 2 2 of Fig. 1 with a portion of 20 the base shown in outline, and Fig. 3 is a front elevation.

In the drawings, A represents the casing of the meter, detachably supported by means of the brackets 2 upon the base B. The nipper-base is bored out to receive the extension-plug 3 of the funnel C. The extension 3 is 25 formed with a longitudinal groove 4, the bottom of the groove registering with the mouth 5 of the funnel.

30 6 represents a plunger arranged to work in the groove 4 and provided with an upwardly-extending arm 7, pivotally connected at its upper end with a link 8. The link has pivotal support 9 in the casing and is pivotally 35 connected with a link 10, which in turn is pivotally connected with a bar 11, provided with teeth 12, which intermesh with the teeth of the pinion 13. The pinion 13 is mounted upon a shaft 14, which shaft carries a pointer

40 15, working in connection with the dial 16. Loosely inclosing the arm 7 of the plunger is a weight 17, which normally holds the plunger lowered.

In using my device the sliver will pass 45 through the funnel 5, by which it is guided into the bottom of the groove 4. As the twine passes underneath the plunger it raises the same and through the medium of the links 8

and 10 and the bar 12 turns the pinion 13 and with it the indicating-needle. The turning of the needle will therefore be dependent upon the thickness of the twine. The numerals upon the indicator-face preferably represent the number of feet of twine to the pound. The funnel-plug is kept from turning by a suitable pin 18.

I claim—

1. A device of the class described, consisting of a base, a funnel removably supported by said base and provided with a groove, a plunger slidable in said groove, an indicator-needle and a lever connection between said needle and plunger.

2. In a device of the class described, the combination of a base, a funnel formed with an extension fitting in said base, said extension being formed with a groove registering with the mouth of the funnel, a plunger slidably arranged in said groove and provided with an upwardly-extending arm, a transverse lever pivotally supported adjacent to the upper end of said arm and having pivotal connection therewith, a link pivotally connecting said lever with a toothed bar, a pinion intermeshing with said bar and an indicating-needle carried by said pinion.

3. A device of the class described consisting of a suitable base, a plug removably arranged in an opening in said base, and provided with a funnel formed with a mouth registering with a groove in said plug, a plunger slidable in said groove, an upwardly-extending arm carried by said plunger, a removable weight inclosing said arm, an indicating-needle and an operative connection between said needle and the upper end of said plunger-arm.

4. In a device of the class described, a base, a cylindrical plug arranged in an opening in said base, having a funnel carried thereby and provided with a mouth registering with the bottom of a groove in said plug, a plunger slidably arranged in said groove, an upwardly-extending arm carried by said plunger, a weight loosely inclosing said arm, a transverse lever pivotally supported adjacent

to the upper end of said arm and having pivotal connection therewith, a link pivotally connecting said lever with a slidably-arranged bar, teeth carried by said bar, said teeth in termeshing with the teeth of an adjacent pinion and an indicating-needle carried by said pinion.

In testimony whereof I affix my signature in presence of two witnesses.

EDWARD M. COLEMAN.

Witnesses:

MARTIN DUFFY,
WILLIAM BINGAMON.
